UNITED STATES PATENT OFFICE.

JAMES A. FIELDS AND JENS THOMSEN SEBLIN, OF CHICAGO, ILLINOIS.

GLOVE-POCKET.

936,437.

Specification of Letters Patent. Patented Oct. 12, 1909.

Application filed May 18, 1908. Serial No. 433,354.

To all whom it may concern:

Be it known that we, JAMES A. FIELDS and JENS THOMSEN SEBLIN, citizens of the United States, residing at Chicago, in the county of Cook and State of Illinois, have invented certain new and useful Improvements in Glove-Pockets, of which the following is a specification.

Our invention relates to gloves and refers especially to attachments therefor.

The chief object of the improvements which form the subject matter of this application is to provide a pocket or receptacle in connection with a glove, which may be used for various purposes but is particularly designed to be employed as a purse for the reception of money so that small change may be conveniently at hand when needed.

Further objects of the invention are to furnish a concealed pocket which will not detract from the appearance or durability of the glove; to provide said pocket with a suitable flap or closure, and to furnish neat, novel and economical methods of forming and attaching the device so as to reduce the manufacturing cost to a minimum.

In carrying out the purposes of the improvements as above set forth, we provide a glove having a pocket attached to its inner surface, the preferred form being illustrated in the accompanying drawing, forming a part of this application, and in which the details are shown in the following views:—

Figure 1 is a front view of a glove with one side of the cuff thrown back to disclose the pocket attached to the inner surface of the article; Fig. 2 is a similar view illustrating a modified form of pocket; Fig. 3 is a longitudinal section on the line 3—3 of Fig. 1; Fig. 4 is a section on the line 4—4 of Fig. 2; and Fig. 5 is a front view of the cuff portion with the sides fastened together.

Referring to the details of the drawing, the numeral 6 indicates a glove made of kid or any other material in common use, having the usual wrist extension or cuff 7, furnished with a slit 7^a, forming flaps 8, 9, common in glove construction, and secured when in position upon the hand of the wearer by ordinary buttons 10. Upon the inner surface of the flap 8 is attached a pocket or pouch 11. In the preferred form shown in Fig. 1, the pocket is formed by securing a piece of suitable material 12 cut to the desired shape, directly to the fabric of the glove. In the view mentioned, the piece 12 is indicated as attached by stitching 13, the line of stitching being omitted upon one side, forming a mouth 14, to permit access to the interior of the receptacle. I have shown the said mouth 14 directed toward the margin 17 of the flap, and as the pocket is illustrated it is applied to a left-hand glove, the indicated direction of the opening making it more convenient of access by the fingers of the right hand, than if the mouth were turned in some other direction. The pocket may, however, be attached to either or both gloves, but in any case the mouth should be directed toward the lateral margin of the flap to which it is attached. The position of the pocket being inside the cuff, when the flaps are drawn together and fastened by means of the buttons 10, the pocket will be firmly clamped between said cuff and the wearer's wrist making it impossible for any of the contents to escape.

Since the glove may sometimes be worn without fastening, or the clasps or buttons may become accidentally separated or fail to hold, and as it is desirable to keep the pocket closed whenever the glove is removed from the hand, I provide a cover for the mouth of the pocket in the shape of a tongue 15. This tongue is formed of a separate piece 16 cut to the desired shape and fastened to the glove by stitching. I prefer to attach this tongue by inserting the margin beneath the edge of the hem 17, with which the wrist portions are usually finished so that a single line of stitching will secure both tongue and hem. The said tongue is provided on the free margin, and is adapted to be slipped beneath a strap 19, on the outer surface of the piece 12. Other fastenings if preferred, may be substituted for the design shown, as this clasp forms no essential part of the invention.

In Figs. 2 and 4 a modified form of pocket is shown, having the body 20 constructed of two continuous layers 21, 22, cemented together at their edges to form a complete pouch or pocket, independent of the glove fabric. The inner layer 21 is continued beyond the outer layer to form the tongue 23, which is adapted to be inserted beneath the strap 19 to form an effective closure as in the case of the previously described construction. This modified form of pocket may be completed before attachment to the glove, and secured in position in any manner desired, either by stitching or by the use

of a suitable adhesive, the latter being the preferred method.

Having thus described our invention what we claim as new, is:—

- 5 1. The combination with a glove having a cuff provided with flaps, of a pocket secured to the inner surface of one of the flaps, the mouth of the pocket being directed toward the lateral margins of said flap, and a closure for the pocket.
- 10 2. The combination with a glove having a cuff provided with flaps, furnished with hems, and a fastening for the flaps, of a pocket secured to the inner surface of one of the flaps, said pocket being arranged with its mouth directed toward the lateral margins of said flap, and a closure for the

pocket, said closure consisting of a tongue attached beneath the hem of said flap.

- 15 3. The combination with a glove having a cuff with an opening in said cuff, of a pocket secured to the inner surface of the cuff and having its opening directed toward the cuff opening, and a tongue for the pocket, said tongue also secured to the inner surface of the glove and adapted to engage the pocket to form a closure therefor.

In testimony whereof we affix our signatures in the presence of two witnesses.

JAMES A. FIELDS.

JENS THOMSEN SEBLIN.
